CARTON FORMING APPARATUS AND METHOD

Grover Cleveland Currie, Bernard David Dans, Maurice B. Dunn, and Joseph Robert Swegleman, Charlotte, N.C., assignors to Dacam Corporation, Charlotte, N.C., a corporation of North Carolina

Application April 6, 1955, Serial No. 499,652

16 Claims. (Cl. 53—29)

This invention relates to packaging machinery and more especially to an improved machine for forming substantially rectangular cartons or carriers from flat cardboard or paper board blanks and wherein articles, such as men's hose and the like, may be placed in the cartons during the process of forming and closing the cartons.

It is an object of this invention to provide an automatic packaging machine having a magazine for receiving a stack of flat substantially cross-shaped carrier blanks or carton blanks, preferably made from cardboard, and including means for feeding the blanks, one at a time, onto a plate of a first folding mechanism which automatically forms each successive blank into the shape of a substantially rectangular four-walled container while projecting the blank downwardly through a rectangular die into one of a series of intermittently movable pockets of predetermined depth.

Thus, the blank is then formed into a container having leading and trailing end flaps and first and second side flaps projecting upwardly from the respective walls of the container and wherein the second side flap is substantially longer than the first side flap. After each successive blank has been formed into said substantially rectangular container, it moves past a station at which articles may be either manually or otherwise placed in each successive container, in the course of which the second relatively long side flap is folded outwardly above the upper edge of the corresponding pocket. Thereafter, each successive container is advanced beneath a folding plate which overlies the path of travel of said pockets so the leading end flap is folded beneath the horizontal folding plate and whereupon a novel form of knock-over cam engages and knocks over the trailing end flap to fold the same so that it will also readily pass beneath the horizontal folding plate.

Thereafter, the relatively short first flap is folded downwardly substantially at the same time that a narrow band of liquid adhesive is applied to the endmost portion of the second flap. The second flap is then overfolded and each successive carton then is advanced to a position in alignment with a transversely reciprocable ejector mechanism which ejects each successive carton or container thus formed into a discharge chute, said chute extending outwardly in substantially right-angular relation to the path of travel of the series of intermittently movable pockets.

As each successive carton is ejected from the corresponding pocket in said series, it is moved beneath a hold-down member which tends to press the top wall thus formed on the carton or carrier against the remainder of the carton to cause the second flap to adhere to the first side flap and, at this time, a printing device prints desired indicia on the bottom of the container thus formed to indicate the style, color, size, etc. identifying the nature of the contents of the corresponding package. Thereafter, as each successive container is subsequently ejected from the corresponding pocket in said series, it

2

engages a previously ejected container to move the containers beneath a normally raised pressure applying mechanism which, during each movement of the series of pockets, moves downwardly and applies pressure to the upper surfaces of the containers therebeneath to thereby press the second flap tightly against the first relatively short flap of the container to insure that they are tightly adhesively interconnected.

Some of the objects of the invention having been stated, other objects will appear as the description proceeds, when taken in connection with the accompanying drawings, in which—

Figure 1 is a side elevation of the improved carton or container forming and sealing apparatus;

Figures 2 and 2-A are, collectively, an enlarged top plan view of the improved machine;

Figure 3 is an enlarged detail elevation of a single revolution clutch mechanism taken substantially along line 3—3 of Figure 2-A;

Figure 4 is an enlarged rear or feed-end elevation of the machine looking at the right-hand side of Figure 1;

Figure 5 is an enlarged fragmentary sectional plan view taken substantially along line 5—5 in Figure 4;

Figure 6 is an enlarged front or discharge end elevation of the improved machine looking at the left-hand side of Figure 1;

Figures 7 and 7-A are, collectively, an enlarged elevation looking at the opposite side of the machine from that shown in Figure 1;

Figures 8 and 8-A are, collectively, a longitudinal vertical sectional view through the machine, Figure 8 being taken substantially along line 8—8 in Figure 2 and Figure 8-A being taken substantially along line 8-A—8-A in Figure 2-A;

Figure 9 is an enlarged fragmentary vertical sectional view taken substantially along line 9—9 in Figure 8-A showing a detail of the valve used for controlling the feeding of carton blanks into the machine;

Figures 10 and 10-A are, collectively, another longitudinal vertical sectional view through the machine looking in the opposite direction from that shown in Figures 8 and 8-A, Figure 10 being taken substantially along line 10—10 in Figure 2-A and Figure 10-A being taken substantially along the line 10-A—10-A in Figure 2;

Figure 11 is a fragmentary elevation, partially in section, similar to the upper left-hand portion of Figure 10-A showing parts of the adhesive or glue applying apparatus in a different position;

Figure 12 is an enlarged transverse vertical sectional view looking toward the blank feeding section of the machine substantially along line 12—12 in Figure 1;

Figure 13 is an enlarged transverse vertical sectional view through the article ejecting mechanism or station looking forwardly substantially along line 13—13 in Figure 1;

Figure 14 (Sheet 7) is an enlarged fragmentary elevation of the printing mechanism looking substantially along line 14—14 in Figure 13;

Figure 15 (Sheet 7) is a sectional plan view taken along line 15—15 in Figure 14;

Figure 16 (Sheet 14) is a plan view showing a form of carton blank which may be folded and formed into a carton, container, or package by the improved machine;

Figure 17 is a somewhat schematic, partially exploded isometric view, with parts in section and parts broken away, showing the manner in which the first folding or forming operation is performed on each successive carton blank;

Figure 18 is another somewhat schematic isometric view showing a mechanism for performing steps subsequent to that shown in Figure 17 including gluing one

of the flaps of the carton, performing second, third and fourth folding operations in sequence, and showing parts of the ejector mechanism and the means for applying pressure to the completed carton to permit setting of the glue or other adhesive;

Figure 19 is an enlarged transverse vertical sectional view taken substantially along line 19—19 in Figure 18, omitting the knock-over cam 63 and the adhesive-applying roller 56;

Figure 20 is an enlarged transverse vertical sectional view taken substantially along line 20—20 in Figure 7-A.

BRIEF SYNOPSIS OF MACHINE

The improved machine or apparatus is particularly devised for feeding flat paperboard or cardboard carton blanks or carrier blanks broadly designated at B, wherein a blank feeding mechanism broadly designated at 10 (Figures 4 and 8-A) picks up the uppermost blank B from a stack and then moves forwardly to deposit the blank upon a die plate or platform 11 of a first folding or forming station broadly designated at 12.

In order to facilitate succeeding steps in the operation of the improved machine, the carton blank B is preferably constructed in the manner to be now described (Figure 16). The carton blank includes a main body portion or bottom 15, opposite side walls 16, 17, a relatively narrow or short side overlap and a relatively wide side overlap or top wall 21. The portions 15, 16, 17, 20 and 21 are disposed in alignment and the blank is suitably scored or creased at the junctures of the side walls 16, 17 with the body portion or bottom 15, as at a, b, respectively. Suitable score or crease lines c, d are also formed at the junctures of the portions 16, 20 and 17, 21.

The body portion 15 also has end walls 22, 23 connected to opposite ends thereof and defined by score lines or crease lines e, f and the outer ends of the end walls 22, 23 have respective flaps 24, 25 thereon defined by score or crease lines g, h, opposite side edges of the blank B being severed or cut for a relatively short length thereof in alignment with the score lines or crease lines g, h, as at i, j, respectively.

Opposite ends of the side walls 16, 17 have respective pairs of small end tabs 26, 27 and 28, 29 thereon, the blank being creased or scored at the junctures of these tabs with the side wall portions 16, 17, as indicated at k, l and m, n, respectively. The outer portions of the tabs 26 to 29, inclusive, are preferably of less width than the side wall portions 16, 17 to form a shoulder 30 on each of said tabs whose length is substantially the same length as each of the corresponding slots i, j so that, when the flaps 24, 25 are folded over the upper edges of the tabs 26, 28 and 27, 29, respectively, in a manner to be later described, the shoulders 30 will penetrate the corresponding cut lines i, j to thereby lock the end walls 22, 23 against the outer surfaces of the respective pairs of tabs 26, 28 and 27, 29.

Referring to Figures 2-A, 8-A, 12 and 17, it will be observed that the substantially horizontally disposed die plate 11 of the first folding mechanism 12 has a substantially cross-shaped opening 35 therein, below which a substantially rectangular tubular die 36 is positioned, this tubular die 36 being of substantially the same internal dimensions as the bottom 15 of the blank B. The tubular die 36 is connected to the distal portions of the wings of the substantially cross-shaped opening in the die plate or platform 11 by means of upwardly diverging inclined die walls 36a to 36d, inclusive. These die walls 36a to 36d, inclusive, are preferably formed integral with the die plate 11 so the portions of the die plate between adjacent inclined die walls 36a to 36c define tab folding projections 40 to 43, inclusive.

As each successive blank B is released by the blank feeding mechanism 10, the corresponding blank is positioned over the cross-shaped opening 35 with the bottom

wall 15 of the blank disposed in vertical alignment with the tubular die 36, whereupon a first fold block or punch 45, which is normally spaced substantially above the die plate 11 and in vertical alignment with the tubular die 36, moves downwardly to press the body portion or bottom 15 of the blank B into and through the tubular die 36. After this operation the blank B is, in fact, a container or carton and will be referred to as such. In so doing, the side walls and end walls 16, 17, 22 and 23 of the blank are folded upwardly at an angle along the respective crease lines a, b, e and f (Figures 16 and 17) and the end tabs 26 to 29, inclusive, are engaged by the respective tab folding projections 40 to 43, inclusive, and thus folded upwardly in substantially right angular relationship to the respective side walls 16, 17 as is clearly shown in Figure 17.

With further downward movement of the punch 45, the side walls 16, 17 are caused to extend upwardly in substantially right angular relationship to the bottom wall 15. In so doing, the tabs 26 to 29, inclusive, substantially overlie the crease lines e, f so the end walls 22, 23 then bear against the outer surfaces of the respective pairs of tabs 26, 28 and 27, 29.

The lower edges of the side walls of the tubular die 36 are spaced above the rear or feed end portions of a pair of laterally spaced longitudinally extending carton side wall guiding bars 46, 46' which are shown in the form of angle bars and between which the upper run or reach of a conveyor, broadly designated at 47, moves. The conveyor 47 is in the form of an endless sprocket chain 50 having a plurality of spaced pockets thereon each of which pockets is formed by a pair of longitudinally spaced angle plates 51, 52. The vertical portions of the angle plates 51, 52 serve as carton end wall supporting elements, the horizontal portions of the angle plates 51, 52 serve as the bottoms of the corresponding pockets for supporting the bottom 15 of each successive carton blank and the carton side wall guide plates 46, 46' serve as the side walls of the pockets.

Thus, the punch plate 45 forces each successive carton blank B downwardly through the tubular die 36 and into a corresponding pocket 51, 52 then positioned therebeneath, the conveyor 47 being advanced in a step-by-step manner, by means to be later described, so the conveyor 47 is stationary as each successive carton thus formed from a blank B is positioned in one of the pockets thereof. It will be observed in the lower left-hand portion of Figure 17 that the flaps 20, 24, 25 remain in substantial alignment with the respective walls 16, 22, 23 of the carton B as each successive pocket in the conveyor 47 is advanced beyond the first folding station 12.

The top wall or large over-flap 21 also extends in substantial alignment with the corresponding wall 17 at this time. However, as the conveyor subsequently advances the corresponding carton B, the inner surface of the wide over-flap or top wall 21 of the corresponding carton B is engaged by a stationary deflecting arm, rod or finger 53 which folds the top wall or wide over-flap 21 of the carton B outwardly along the crease line d, against the upper edge of the side wall guiding bar 46. The lateral plane of the portion of the machine at which the deflecting rod or finger 53 is disposed may be termed as a carton loading or filling station, since the rod or finger 53 holds the top flap or wall 21 of the carton B in open position so that articles, such as men's hose, may be either manually or automatically placed in each successive carton as it is positioned adjacent the forward free end of the deflecting rod or finger 53.

Thereafter, each successive carton, as formed thus far from a corresponding blank B, is passed through a second folding and gluing or adhesive applying station broadly designated at 55 which includes a continuously driven glue-applying or adhesive-applying wheel or roller 56 (Figures 7-A, 9, 10-A, 18 and 20) to whose periphery a supply of liquid adhesive or glue is applied by means to be later described. The second folding mechanism is

in the form of an angle plate broadly designated at 57 and includes a substantially horizontally disposed plate member 60 which overlies the corresponding portions of the side wall guiding plates 46, 46' in closely spaced relationship thereto and whose rear edge is turned upwardly, as at 61, and is also formed with a relatively narrow opening or slot 62 therein (Figures 18 and 19).

The rear portion of plate 60 serves as a leading end flap folding means, since the rounded rear edge 61 of plate 60 is disposed in the path of the end flap 24, on the wall 22 of the carton B, and folds this flap 24 downwardly in substantially parallel relation to the bottom 15 of the carton B. It will be noted (Figure 19) that the rear portion of the plate 60 also extends laterally outwardly beyond the vertical plane of the side wall guiding bar or plate 46 to thereby insure that the top wall flap 21 remains in an outward position with respect to the corresponding pockets 51, 52.

As each successive carton formed from a blank B is advanced to a position beneath the rear portion of the plate 60, a trailing end flap folder in the form of a knock-over cam 63 (Figures 6, 8, 18 and 20), whose lower portion, at times, extends partially through the opening 62 in the rear portion of plate 60, momentarily rotates in a clockwise direction in Figure 18 as a step is imparted to the conveyor 47 so that a flat radially projecting surface 64 on the cam 63 engages the outer or rear surface of the end flap 25 to move the same downwardly and forwardly. Since the corresponding carton B is also in the course of forward movement at this time, the end flap 25 then engages the rounded surface 61 and is deflected beneath the plate 60 and thus folded in perpendicular relationship or right-angular relationship to the rear end wall 23.

Upon completion of the latter step the relatively short top flap 20 is positioned against the inner surface of an auxiliary side wall guiding member 65 alined with the inner surface of the side wall guiding plate 46'. The auxiliary side wall guiding member 65 is spirally formed at 66 thereby forming a short flap overfolding member which folds the flap 20 inwardly and downwardly in horizontal position overlying the bottom 15 of the carton B. The plate 60 has an opening or cut away portion 67 therein through which the short overflap 20 passes in advance of its passing beneath the horizontal portion of plate 60.

Now, it will be noted that the medial portion of plate 60 is recessed at its free edge remote from the vertical portion 65 of angle plate 57, as at 70, and a spirally formed top wall over-flap folding element 71 is positioned adjacent the recess 70. In the course of movement of each successive carton blank B before it approaches the top wall folding element 71, the then upper surface of the top wall 21 of carton B is engaged adjacent its free edge by the adhesive applying roll or wheel 56. This provides a relatively narrow strip of adhesive such as is indicated at 21a in Figure 16, whereupon the top wall 21 is then over-folded by element 71 to extend at a slight angle to the horizontal as it overlies the medial portion of the plate 60.

It will be observed that the foremost end of plate 60 is also cut away to provide a relatively large recess or opening 72 therein over which the inner portion of a carton ejection hold-down plate or element 73 is disposed. It will be noted that, as each successive pocket 51, 52 is positioned in alinement with the recess or opening 72 in the front end of plate 60, it is then positioned beneath the rounded or pointed inner portion of the carton ejection hold-down plate 73. This carton ejection hold-down plate 73 is inclined downwardly and to the left in Figure 13 so that, as the top wall 21 of the carton B is moved a step in an ejection operation, by means of a lateral portion 74 on an ejector plunger 75, the carton ejection hold-down plate 73 presses the top wall of the carton B downwardly so that the adhesive surface 21a (Figure 16) en-

gages the then upper surface of the relatively short top wall flap 20.

Of course, as the ejector plunger 75 moves from right to left in Figure 13, it is apparent that this occurs in the interim between successive steps of the conveyor 47 and, thus, the completed carton formed from a blank B is projected into a horizontal chute or guideway broadly designated at 76. It will be noted that the ejection chute or guideway 76 is provided with side walls 77, 78 whose lower edges are connected to a bottom wall 81 which is slotted throughout its length, as at 82. The inner end of each of the side walls 77, 78 of the ejection chute 76 is slotted to form variant length projections 83, 84 thereon whose innermost ends are rounded somewhat to guide each successive carton into the chute 76.

As each successive filled carton is projected into the chute 76, suitable identifying indicia is applied thereto to indicate the color, style, etc. of the article or hose then positioned in the corresponding carton. To this end, it will be best observed in Figures 13, 14 and 15 that a printing device, broadly designated 85, is provided which comprises a printing block 86 to the upper surface of which a printing plate 87 is suitably secured, said printing plate 87 having suitable raised letters or other indicating medium thereon. The printing block 86 is carried by a vertically reciprocable printing plunger or arm 90 which is controlled, by means to be later described, to move upwardly immediately after a suitable ink pad 91 (Figure 13), impregnated with ink, moves inwardly from the position shown in Figure 13 to a position above the printing plate 87. Thus, as the plate 87 moves upwardly, it engages the ink pad 91 and some of the ink is thus transferred to the raised characters on the printing plate 87.

The upward movement of the printing plate 87 is uninterrupted, once effected, however, the ink pad 91 is then withdrawn and the raised characters on the printing plate 87 subsequently move upwardly through the slot 82 in the discharge trackway or guideway 76 and impinge against the lower surface of the bottom or body portion 15 of the carton B to thereby provide indicating indicia on each successive carton formed from a blank B.

As the next succeeding carton is ejected from the conveyor 47, it engages the preceding carton and advances the same along the chute or guideway 76 beyond the outer edge of the carton ejection guide plate 73 and beneath an intermediate hold-down bar 95 and a pair of resilient clamping elements (Figures 2, 13 and 18) which straddle and extend longitudinally of the intermediate hold-down bar 95. Although the hold-down bar 95 is spaced substantially above the normal level of the upper surface of each successive filled carton resting upon the bottom wall 81 of the chute 76, this bar 95 is provided to limit upward movement of the overfolded cover or top wall 21 of the corresponding carton B in the event that it does not initially adhere to the narrow overfolded flap 20.

As each successive carton passes to a position beneath the resilient clamping elements 76, a clamping plate 97, to which the clamping elements 96 are suitably secured, is dropped from a raised position so the clamping elements 96 engage and press the top wall 21 of the corresponding carton against the portions of the carton therebeneath to particularly cause the adhesive material applied to the cover or top wall 21 of the carton B to tightly seal the top wall 21 in engagement with the narrow side overflap 20. The hold-down or clamping plate 97 is raised during each movement of the cartons along the chute 76.

It will be observed in Figures 2, 4, 6 and 13 that the chute 76 has a pair of longitudinally spaced transverse bars 100, 101 suitably secured to the upper edges of the walls 77, 78 thereof, to each of which a plurality of leaf-spring pressure applying plates or members 102 are suitably secured and which, during the course of further movement of each successive carton along the chute 76, applies further pressure to the upper surfaces of the filled

cartons so that, when the cartons are finally ejected from the free outer end of the guideway or chute 76, the top walls 21 will have tightly adhered to the upper surfaces of the side overflaps 20.

A suitable container, not shown, may be provided beneath the free end of the discharge chute or guide way 76 for receiving each successive carton as it is ejected from the discharge chute 76. The description thus far is given to provide a general understanding of the entire machine, particularly as to those parts which contact the blank from the time that it is in its flat stage at the stack to the time at which the completed carton is discharged from the machine. The various operating elements of the machine will now be described in detail.

Frame and machine drive

The frame of the machine comprises an elongated base 110 to which left-hand and right-hand side frame members 111, 111' are suitably secured, the left-hand frame member 111 being spaced inwardly from the left-hand side of the base 110 as is most clearly shown in Figures 2, 2-A, 4 and 20. The side frame members 111, 111' are spanned by front and rear conveyor-track-supporting transverse frame members or plates 114 and a pair of spaced transverse first folding guide supporting frame members 115, 116 (Figures 2-A, 4, 8, 10 and 12).

The main drive for the machine includes an electric motor 120 fixed on a base 121 (Figures 1 and 2) adjustably supported on a pair of guide rods 122 and on a screw 123. The guide rods 122 and screw 123 are mounted in standards 124 fixed to the base 110 and the screw 123 has a hand-wheel 125 thereon for adjusting the motor 120 longitudinally of the base 110. The shaft of the electric motor 120 has a variable pitch pulley assembly 126 mounted thereon which is engaged by an endless belt 127 (Figures 1, 2, 4 and 6). The endless belt 127 is also mounted on a relatively large pulley 130 fixed on the outer end of a shaft 131 journaled in a standard or bracket 132 fixed to the base 110. Shaft 131 is also journaled in the left-hand side frame member 111.

A pinion 133, also fixed on shaft 131, engages a relatively large gear 134 fixed on the outer end of a shaft 135 (Figure 2-A) journaled in bracket 132 and in the left-hand side frame member 111. Shaft 135 also has a relatively small gear or pinion 136 fixed thereon which engages and continuously imparts rotation to a relatively large gear 137 loose on a shaft 140 journaled in the standard or bracket 132 and in both side frame members 111, 111' (Figures 4, 7, 8-A, 10 and 12). The gear 137 also has a sprocket wheel 141 fixed thereon which drives the gluing mechanism or adhesive applying mechanism 55 in a manner to be later described.

The gear 137 also has a clutch plate 142 fixed to the inner surface thereof which is a part of a manually controlled single-revolution clutch mechanism which may be of any desired construction and is shown as being of a type disclosed in Figures 34 to 37, inclusive, of U.S. Patent No. 2,677,221 issued to Grover C. Currie et al. Accordingly, only so much of the single-revolution mechanism will be described as is necessary to a clear understanding of the present invention. It will be observed in Figures 3 and 12 that the periphery of the disk or clutch plate 142 is provided with a plurality of circularly spaced notches 143, any one of which may be engaged by a dog, not shown in the present drawings, but being clearly shown in said patent, carried by a clutch arm 144 fixed on the dog shaft 140. The dog and clutch arm 144 are normally maintained stationary by a knife mechanism 145 mounted on a lever 150 normally urged upwardly into engagement with the arm 144 by a tension spring 151.

The arm 150 is fixed on one end of a transverse rocker shaft 152 suitably journaled in the side frame member 111, 111' (Figures 2-A, 4, 7, 8-A, 10 and 12). The end of rocker shaft 152 remote from the clutch operating lever 150 has a crank 153 fixed thereon to which one end of an

adjustable link 154 is pivotally connected. The lower end of link 154 is pivotally connected to a treadle plate 155. The treadle plate 155 is fixed on a shaft 156 (Figure 12) journaled in bearing blocks 157 fixed to the corner responding side of the base 110.

It is thus seen that an operator sitting or standing adjacent the right-hand side of the machine and laterally of the cover outfolding or deflecting rod 53 may depress the treadle plate 155 whenever he desires to impart a step in movement to the conveyor 47 to effect a cycle in the operation of the machine. In so doing, the treadle plate 155 causes rocker shaft 152 to rotate in a counterclockwise direction in Figure 7 or in a clockwise direction in Figure 3 to thereby move the clutch actuating lever 150 downwardly (and thereby effecting an operation of the single revolution clutch) so the disk 142 then imparts a complete revolution to the clutch arm 144 and shaft 140.

Drive for conveyor

With each complete revolution of the cam shaft 140, in the manner heretofore described, a single step in movement is imparted to the main conveyor 47 in a manner which will now be described in detail. It will be observed in Figure 12 that the cam shaft 140 has a sprocket wheel 160 fixed thereon which is disposed closely adjacent the inner surface of side frame member 111. By referring to Figures 10 and 10-A, it will be observed that the sprocket wheel 160 is engaged by an endless sprocket chain 161 which also engages a sprocket wheel 162 (Figure 6) fixed on a second or rear cam shaft 163 suitably journaled in the side frame members 111, 111'. Suitable means are provided for maintaining tension in the sprocket chain 161 and, referring to Figure 10 it will be observed that the sprocket chain 161 is engaged by an idler sprocket wheel 165 journaled on a stub shaft 166 fixed to one end of an arm 167. The outer end of said arm 167 is adjustably secured to the inner surface of side frame member 111 by means of a screw 170. The arm 167 also has one end of a hand-lever 171 fixed thereto which may be manipulated by the operator for adjusting the position of the arm 167 about the screw 170.

Referring to Figures 6, 7-A and 20, it will be observed that the cam shaft 163 has a face cam 173 fixed thereon which is provided with an irregular groove 174 in one side thereof which is engaged by a follower 175 projecting outwardly from a follower arm or yoke arm 176 whose bifurcated front end straddles and is guided on the shaft 163. The rear end of the follower arm 176 in Figure 7-A has an overriding mechanism thereon including a pivoted lever 180 which is normally urged upwardly against the rear end of the follower arm 176 by a compression spring 181. The compression spring 181 is carried by an adjustment screw 182 which loosely penetrates the outer portion of the lever 180 and is threadably embedded in the rear end of the follower arm 176.

The follower arm 176 and the safety lever or overriding lever 180 are recessed to form a seat for a stub shaft 183 to which the lower end of a segmental gear arm or lever 184 is fixedly secured. The rearmost end of the follower arm 176 has a normally open switch 185 fixed thereto and it is thus seen that, in the event of any obstruction preventing advancement of the conveyor 47, the follower arm 176 may move rearwardly relative to the pivot shaft 183 and seat for the pivot shaft will thus be moved rearwardly beyond the pivot shaft 183 which will then cause the lever 180 to move away from the main portion of the follower arm 176. This permits the switch 185, which is normally held in closed position by the lever 180, to open and thereby break the circuit to the electric motor 126, since the switch 185 is interposed in the circuit to the electric motor 126.

The segmental gear lever 184 is pivoted intermediate its ends, as at 186, on a bearing block 187 suitably secured to the outer surface of the side frame member 111'. The upper end of lever 184 has a segmental gear or gear segment 190 fixed thereon or integral therewith which meshes with

a pinion or gear 191 loose on one end of a transverse shaft 192 suitably journaled in the side frame members 111, 111' (Figures 2, 6 and 13). The medial portion of the transverse shaft 192 has a sprocket wheel 193 fixed thereon which is engaged by the endless sprocket chain 50 of the conveyor 47 (Figures 1, 2, 6, 7-A, 8 and 13).

In order to restrain the conveyor 47 from movement in either direction in the interim between each step thereof, it will be observed in Figures 8 and 13 that the sprocket 193 has a disk 194 fixed to one side thereof which is provided with a plurality of equally spaced notches 195 in the periphery thereof. The notches 195 are adapted to be successively engaged by a key or stop member 196 on the upper end of a crank or lever 197 whose lower ends are pivotally mounted on a transverse pivot shaft 200 suitably journaled in the side frame members 111, 111' (Figures 8 and 13).

The medial portion of crank 197 has the rear end of a link 201 pivotally connected thereto whose front end is pivotally connected to one end of a crank arm 202 pivotally mounted intermediate its ends on a stub shaft 203 suitably secured to the side frame member 111'. The hub of the crank arm 202 has an offset crank arm or follower arm 204 thereon. A follower 205 on the lower end of arm 204 engages the periphery of an irregularly-shaped cam 206. The cam 206 is fixed on the rear cam shaft 163 heretofore described.

As heretofore stated, the pinion or gear 191 is loose on shaft 192 and, in order to transmit a step in rotation to the shaft 192 from the gear 191 each time a reciprocatory movement is imparted to the gear 191 by the gear segment 190 (Figures 2 and 7-A), the gear 191 has a pawl-carrying arm 210 fixed thereto which is also loose on the shaft 192. A ratchet pawl 211 is pivotally mounted on the outer portion of arm 210 and rests against the periphery of a ratchet wheel or cog wheel 212. The ratchet wheel 212 has a plurality of equally spaced projections 215 thereon which correspond substantially with the notches 195 in the periphery of the locking disk 194 (Figures 7-A and 8).

The ratchet wheel 212 is fixed on the one end of the shaft 192. Thus, with each movement of arm 210 in a clockwise direction in Figure 7-A, the pawl 211 engages one of the projections 215 on the ratchet wheel 212, immediately after the high point of cam 206 (Figure 8) has moved into engagement with the follower 205, so the key 196 is out of engagement with the locking disk 194 as a quarter-revolution is imparted to the ratchet wheel 212 and shaft 192. This imparts a step in movement to the conveyor 47. The cam 206 is so formed that the high portion thereof will move out of engagement with the cam follower 205 before a complete step in movement has been imparted to the ratchet wheel 212, shaft 100 and conveyor 47, so the spring 207 causes the key 196 on crank arm 197 to resiliently engage the periphery of the locking disk 194 before the next succeeding notch 195 registers with the key 196.

Thus, upon exactly one-quarter revolution being imparted to the shaft 192, the key 196 then drops into the next succeeding notch 195 in the periphery of the locking disk 194 to prevent further movement of the conveyor 47 in either direction. It follows that, with the subsequent movement of the gear segment 190 in a clockwise direction in Figure 7-A, the key 196 prevents rotation of the shaft 192 although the gear 191 is then rotating in the opposite direction and returns the ratchet pawl 211 to substantially the position shown in Figure 7-A.

Referring to Figures 8-A and 12 it will be observed that the rear portion of the endless conveyor chain 50 is mounted on a sprocket wheel 215 fixed on the medial portion of a transverse shaft 216 whose opposite ends are suitably journaled on the side frame members 111, 111'. In order to maintain the upper run or reach of the main conveyor 47 straight throughout its length between the sprocket wheels 193, 215 or, in other words, on a substantially horizontal plane longitudinally of the machine, a conveyor track assembly, broadly designated at 217, is provided

which is substantially channel-shaped throughout its length and whose opposite ends terminate short of the respective sprocket wheels 193, 215.

The track assembly includes a horizontal bottom 220 (Figures 8, 8-A and 19) and spaced side tracks 221, 221' which support the outer edge portions of the pocket angles 51, 52 during the course of movement thereof with the upper reach or run of the conveyor 47. The upper portions of the pocket tracks 211, 211' have respective bars or projections 222, 222' on the outer surfaces thereof whose rear ends terminate adjacent the rear ends of the side tracks or pocket supporting tracks 221, 221' and whose front ends terminate short of the lateral plane of the carton ejection chute or guideway 76.

As best shown in Figures 4, 12, 13, 17, 18 and 20, the carton guiding side plates or pocket side walls 46, 46' are in the form of angle bars whose horizontal portions are suitably secured to the upper surfaces of the respective bars or projections 222, 222' carried by said pocket supporting tracks 221, 221'. It will also be observed in Figure 18 that the front end of the pocket side plate 46' terminates flush with the rear end of the short overflap guiding member 65 of the second fold mechanism 57. As shown in Figure 19, the portion 65 of angle plate 57 extends downwardly remote from the top wall overfolding member 71 and is then bent outwardly and is suitably secured to the upper surface of the bar 222'.

Also, referring to Figure 18 it will be observed that the top wall overfolding element 71 has a rearwardly extending plate portion 71a integral therewith against which the top wall 21 of each successive carton is positioned during the application of adhesive thereto in the manner heretofore described. The lower portion of the plate portion 71a of the top wall overfolding element 71 is suitably secured to the outer edge of the bar or projection 222 heretofore described. Spaced between the side tracks or pocket supporting tracks 221, 221', and extending longitudinally of the track assembly 217, is a chain guiding track 225 which is of slightly lesser horizontal thickness than the distance between opposed links of the sprocket chain 50 and upon which those rollers of the sprocket chain moving with the upper reach or run of the conveyor 47 ride to thereby maintain the entire length of the upper run of the conveyor 47 in straight substantially horizontal position. The chain guiding track 225 is suitably secured to the upper surface of the track assembly bottom 220. It will be best observed in Figures 8 and 8-A that opposite ends of the track assembly bottom 220 are suitably secured to the upper surfaces of the transverse frame members 112, 113.

Carton blank magazine and feed mechanism

As heretofore stated, with each successive cycle in the operation of the machine, a blank B is delivered from a stack and fed onto the die plate or platform 11 of the first folding mechanism 12 by means of a feed mechanism 10. Disposed adjacent the feed mechanism 10 is a magazine broadly designated at 230 which comprises a vertically movable stacking platform or elevator platform adapted to support a stack of flat blanks B and which is mounted for vertically sliding movement on front and rear vertically disposed guide posts 232, 232' and 233, 233'. The front guide posts 232, 232' are fixed to the inner faces of a pair of stationary magazine side plates or walls 234, 234' (Figures 2-A, 4, 8-A, 10 and 12). The magazine side plates or side walls 234, 234' are suitably supported by the side frame members 111, 111', there being respective spacers 235, 235' disposed between the proximal surfaces of the magazine side plates 234, 234' and the side frame members 111, 111'.

It will be observed in Figure 2-A that the guide posts 232, 232', 233, 233' are spaced from each other preferably so the opposite side portions of the blank will fit therebetween when the blanks are stacked on the elevator platform 231. In this instance, the portions 20 and 21 of the blank B (Figure 16) may be positioned between

the respective sets of guide posts 232, 233' and 232, 233. Thus, in order to facilitate loading the magazine 230, the rear guide posts 233, 233' are mounted on respective auxiliary magazine side plates 236, 236' which are relatively narrow as compared to the main magazine side walls or plates 234, 234' and whose front edges are hingedly connected to the rear edges of the respective magazine side plates or side walls 234, 234'. In order to maintain the guide posts 233, 233' in the operative position shown in Figures 2-A and 4, it will be noted that the lower portions of the guide posts 233, 233' have opposite ends of a tension spring 237 suitably connected thereto (Figure 4).

It will be observed in Figures 4, 8-A and 12 that the elevator platform or stacking platform 231 is fixed on the upper end of an upright support or plate 240 mounted for vertical sliding movement in the transverse frame member 114. The frame member 114 has a vertically extending slot 241 therein (Figure 5) in which the upright support or plate 240 is loosely mounted, said plate 240 being retained in the slot 241 by a pair of guide plates 242, 242' suitably secured to the front surface of the transverse frame member 114.

Suitably secured to the rear surface of plate 240 is a rack 243 which is engaged by a pinion 244 fixed on a transverse shaft 245. The shaft 245 is journaled in frame member 111' and in a bearing block 246 suitably secured to the guide plate 242 (Figures 5, 10 and 12). It will be observed in Figures 2-A, 4, 7 and 12 that the outer end of the shaft 245 has a stack raising or elevator raising mechanism thereon which comprises a ratchet wheel 247 and hand-wheel 250, both being fixed on shaft 245.

The ratchet wheel 247 is engaged by a feed pawl and hold-back pawl 251, 252 (see Figure 7). The hold-back pawl 252 is normally held in engagement with the ratchet wheel 247 by an overbalanced hand-lever 253 integral with or suitably secured to the hold-back pawl 252. The pawl 252 and hand-lever 253 are pivotally mounted at their juncture, as at 254, on the side frame member 111'. The feed pawl 251 is fixed to the medial portion of a pawl-carrying arm 255 pivotally mounted on a rocker arm 256 which is oscillatably mounted intermediate its ends on the shaft 245.

It will be noted in Figures 2-A and 7 that the hand-lever 253 has an abutment or pin 257 projecting therefrom which is adapted to engage the free end of the pawl-carrying arm 255 when the hand-lever 253 is manually moved in a counterclockwise direction in Figure 7. The abutment 257 then engages the free end of pawl-carrying arm 255 so that both of the pawls 251, 252 are moved out of engagement with the ratchet wheel 247 whereby the elevator platform or stacking platform may be raised and lowered by manual rotation of hand-wheel 250.

The upper end of a rocker arm or lever 256 in Figure 7 is pivotally connected to the rear end of a connecting rod 260 whose front end is pivotally connected to the upper end of a cam lever 261 oscillatably mounted intermediate its ends on a stub shaft 262 projecting outwardly from the side frame member 111'. The lower end of cam lever 261 has a cam follower 263 thereon which is adapted to, at times, be engaged by the periphery of an irregularly-shaped cam wheel 264 fixed on the rear transverse cam shaft 140. The cam follower 263 is normally urged toward cam wheel 264 by a tension spring 265 connected to the lower portion of rocker arm 256 and to the side frame member 111'.

However, the cam follower 263 is, at times, restrained from engaging the low surface of cam wheel 264 by an electrically operable latch or restraining mechanism which is best shown in the lower left-hand portion of Figure 7. In this instance, the lower end of rocker arm 256 has a hook member 266 thereon which is engaged by a latch member 267 fixed on the free end of a latch arm or lever 270 pivotally supported on the side frame member 111'. The latch arm 270 is normally urged up-

wardly against a stop or abutment 271, carried by the side frame member 111', by a tension spring 268.

The medial portion of latch arm 270 is pivotally connected to the upper end of a solenoid plunger 269 surrounded by a solenoid coil 269a fixed in a suitable housing 269b carried by the side frame member 111'.

The solenoid coil 269a is interposed in an electrical circuit in which a normally open switch 274 is also interposed. The switch 274 is suitably supported by a side frame member 111' and is adapted to be closed, at times, by a switch closing member or plate 271 suitably secured to the lower end of a vertically reciprocable carton blank lift bar 272 which is a part of the blank feeding mechanism 10 now to be described in detail. A conduit 273 (Figure 7) has suitable conductors therein connecting coil 269a with switch 274.

Blank lifting and feeding apparatus or mechanism

The blank raising and feeding mechanism comprises a plurality of vacuum controlled carrier blank or carton blank grasping or transferring devices each of which is designated at 275, there being two of these shown in Figures 2-A and 10, in the form of a resilient inverted suction cup. Each of the suction cups 275 is communicatively connected to the lower end of a tube or pipe 276. The upper portions of the two tubes or pipes 276 are suitably secured to or integral with the legs of a bracket 277 which, as shown in Figure 2-A, is substantially U-shaped in plan and is suitably secured to the inner surface of the vertically reciprocable carrier blank raising bar 272.

It will be observed in Figures 2-A, 4, 7, 8-A and 12 that the blank lift bar 272 is mounted for vertical sliding movement in a horizontal feed carriage or bracket 280 which is mounted for horizontal movement parallel to the longitudinal axis of the machine on a horizontally disposed feed carriage guide bar 281 suitably secured to the inner surface of the side frame member 111'. The upper end of the carton blank lift bar 272 extends above the horizontal feed carriage 280 and has a roller or follower 283 thereon which is adapted to ride in a groove 284 provided in the inner surface of a horizontally disposed tiltable track 285 (Figures 4, 7, 8-A and 12). The tiltable track 285 extends substantially longitudinally of the machine and is fixed intermediate its ends on a stub shaft 286. The medial portion of shaft 286 is journaled in a standard 287 which extends downwardly and is suitably secured to the side frame member 111'. The outer end of shaft 286 has a crank 290 fixed thereon to which the upper end of a link 291 is pivotally connected. The lower end of link 291 (Figure 7) is pivotally connected to one arm of a bell crank 292 which is also oscillatable on the stub shaft 286 heretofore described. The other arm of bell crank 292 has a cam follower or roller 293 thereon which is adapted to, at times, engage the periphery of an irregularly-shaped cam wheel 294 fixed on the rear cam shaft 140. The function of cam wheel 294 will be later described.

It will be noted, however, that the cam follower 293 is normally urged toward the periphery of cam wheel 294 by a tension spring 295 whose upper end is suitably connected to the rear end of the tiltable track 285, as by means of a bracket 296, and whose lower end is connected to a spring anchor 297 suitably secured to the rear edge of the upright side frame member 111'. It will be observed in Figures 7 and 8-A that the carriage 280 is relatively short as compared to the length of guide bar 281 and has the rear end of a link 300 pivotally connected thereto, whose front end is pivotally connected to the upper end of a crank 301.

The crank 301 extends downwardly in Figure 5 and is pivotally mounted on a stub shaft 302 projecting outwardly from side frame member 111'. Crank 301 has a segmental gear or gear segment 303 thereon which engages a vertically disposed rack 304. The rack 304 is

mounted for vertical sliding movement in a guide block 305 suitably secured to the outer surface of side frame member 111'. In Figure 7, guide block 305 is cut away to provide an opening therein through which the gear segment 303 projects. The lower end of rack 304 has a yoke 306 thereon which straddles and is guided upon the hub of a face cam wheel 307 having an irregular groove 308 in one face thereof which is engaged by a cam follower or roller 311 carried by the yoke 306.

The periphery of cam wheel 307 (Figure 7) has a shoulder 312 thereon which is adapted to be engaged, at times, by an adjustable abutment or screw 313 on the free end of a locking arm 314. The locking arm 314 is pivotally mounted, as at 315, on the side frame member 111' and is normally urged toward the periphery of cam wheel 307 by a tension spring 316. The locking arm 314 with its adjustable abutment 313 is merely provided to prevent reverse rotation of the cam shaft 140 in the interim between each operation of the single revolution clutch comprising elements 142, 143 and 144 in Figures 3 and 12.

Suction means for vacuum controlled transferring devices

Referring to Figures 2-A, 4, 7, 8-A and 12, it will be observed that each of the tubes 276, on which the blank transferring devices 275 are mounted, has one end of a resilient conduit 320 communicatively connected thereto which are connected by suitable pipe fittings 321, to a resilient conduit or pipeline 323 which extends upwardly, curves forwardly and then downwardly and whose lower end is communicatively connected to a pipeline 324 (see Figures 8-A and 12) in which a pipe T 325 is interposed. The pipe T 325 has one end of a pipe or conduit 326 communicatively connected thereto which extends to the right in Figure 12, then rearwardly and then outwardly and is communicatively connected to a suitable motor driven air compressor assembly generally designated at 330, the motor of which is suitably secured to the base 110 of the machine frame.

The motor of said compressor assembly has electric wires 331 connected thereto which lead to a suitable source of electrical energy and it is thus seen that the compressor assembly 330 creates negative pressure in the suction cups 275 and the intervening connections heretofore described. However, it is apparent that the suction created in the suction cups 275 must be relieved for releasing each successive carrier blank or carton blank B from the suction cups as each successive blank B is positioned upon the die plate 11. To this end, it will be observed that the lower end of the pipeline 324 in Figures 8-A, 9 and 12 is communicatively connected to an inverted cup-like valve body 332 whose lower end is adapted to be opened and closed by means of a valve plate 333, preferably made from a resilient material such as rubber, leather or the like.

The valve plate 333 is fixed to a reinforcing plate 334 and both the valve plate and reinforcing plate are loosely mounted on a vertically disposed shaft 335 whose lower end is suitably secured to the medial portion of a valve control arm 336. The valve plate 333 is normally urged upwardly toward an abutment 337 on the upper end of the shaft 335, by a compression spring 340, the abutment 337 being shown in the form of a pair of nuts, in this instance.

Referring to Figure 8-A, it will be observed that the cup-like valve body 332 is fixed to or integral with a bracket 341 suitably secured to the inner surface of the side frame member 111', and to which the rear end of the valve control lever 336 is pivotally connected. The front end of said valve control lever 336 has a follower 342 thereon which is urged against the periphery of a cam wheel 343, by means of a tension spring 344 whose upper end in Figure 8-A is connected to the free end of the valve control lever 336 and whose lower end is connected to the side frame member 111'.

It is apparent, by referring to Figures 8-A, 9 and 12, that the valve plate 333 will occupy the closed position shown in Figures 8-A and 9 when the follower 342 is engaged by the high surface of the cam wheel 343 and, when the low surface of cam wheel 343 engages the follower 342, the valve control lever 336 will then have moved downwardly to permit air to enter the valve body 332 and to thereby prevent the occurrence of negative pressure in the suction cups 275. The cam wheel 343 is fixed on the rear cam shaft 140.

It is thus seen that, in operation, the high surface of cam wheel 294 (Figure 7) moves out of engagement with cam follower 293 and permits the tension spring 295 to swing the tiltable track 285 downwardly at its rear end, thus moving the suction cups 275 (Figure 8-A) downwardly from the position shown in Figures 8-A and 12 and into engagement with the uppermost of the blanks B then positioned on the elevator platform 231. At this time, the high surface of cam 343 is in engagement with follower 342 so that suction is then created in the suction devices or transferring devices 275 whereby the uppermost carton blank or carrier blank B in said stack will then adhere to the lower ends of the suction devices or transferring devices 275.

Now, each time the suction cups 275 move downwardly in the manner last described, they do not necessarily move downwardly to their extreme lowermost limits, since they resiliently engage the upper surface of the then uppermost carton blank or carrier blank in the stack positioned upon the elevator platform 231. Accordingly, the cam follower 293 (Figure 7) may then be spaced from the low surface of cam wheel 294. However, upon a predetermined number of operations of the suction devices as last described, say, upon engaging every fourth carton blank, the blank lift bar 272 will then be enabled to move downwardly sufficiently to where the switch engaging plate 271 engages and closes the normally open switch 274 to thereby close the circuit to the solenoid coil 269a.

It is apparent that, when the solenoid coil 269a is energized momentarily in the manner heretofore described, the latch arm 270 moves downwardly in Figure 7 to thereby release rocker arm 256 at substantially the time that the low surface of cam wheel 264 registers with the follower 263 on cam lever 261. Thus, the tension spring 265 then rotates rocker arm 256 a partial revolution in a counterclockwise direction in Figure 7 and, with the subsequent engagement of the cam follower 263 by the high portion of cam wheel 264, it is apparent that a step in rotation will be imparted to the ratchet wheel 247 and shaft 245 to thereby raise the elevator platform 231 a predetermined amount. Of course, when the rocker arm 256 subsequently returns to the position shown in Figure 7, the flow of current to the solenoid coil 269a will have been broken, since the suction device lift bar 272 will have moved upwardly by this time so the latch 267 will then engage the hook member 266 on the lower end of rocker arm 256 to prevent further oscillation thereof until the switch 274 is again closed in the manner heretofore described.

It is apparent that the suction device lift bar 272 is moved upwardly by the high surface of cam wheel 294 engaging follower 293 on the bell crank 292. This returns the tiltable track 284 to substantially the position shown in Figures 7 and 8-A.

As the suction device lift bar 272 returns to elevated position, the low portion of the groove 308 in face cam 307 (Figure 7) engages the follower 311 on yoke 366 thereby permitting the rack 304 to move downwardly to, in turn, impart movement to the crank 301 in a clockwise direction in Figure 7 and to thereby cause the carriage 280 to move forwardly from substantially the position shown in Figure 7 to where the suction cups 275 are positioned above the die plate 11 heretofore described.

It is apparent that the roller 283 on the upper end of the

suction device lift bar 272 then traverses the groove 284 in the tiltable track 285. Suitable adjustable stops 347, 348 (Figure 8-A) are provided on opposite ends of the feed carriage guide bar 281 for limiting rearward and forward movement of the horizontal feed carriage 280.

When the suction devices 275 have reached their foremost position, the low surface of cam wheel 343 (Figure 8-A) moves into engagement with follower 342 to open the valve 333 and to thereby release the carton blank or carrier blank B from the suction devices 275. At this time, the first folding punch plate 45 is in elevated position above the level of the die plate 11 so the corresponding blank B is positioned above the cross-shaped opening 35 in the die plate 11 preparatory to the first folding operation being effected in the manner heretofore described. The operating parts of the first folding mechanism 12 will now be described in detail.

First folding mechanism

The punch plate 45 is fixed on the lower end of a vertically reciprocable post or column 350 (Figures 1, 2-A, 4, 7, 8-A, 12 and 17) which is mounted for vertical sliding movement in a bracket 351 which extends outwardly (Figure 12) and is suitably secured to the inner surface of the side frame member 111'. The upper portion of the column 350 (Figure 8-A) has a substantially rectangular block 352 pivotally mounted thereon which is engaged by the bifurcated front end of a crank 353 whose rear end is fixed on a shaft 354. The medial portion of shaft 354 is journaled in the upper portion of a bearing block or bracket 355 (Figures 2-A, 4, 10 and 12) whose lower portion is suitably secured to the left-hand side frame member 111. The outer end of shaft 354 has a crank 356 fixed thereon to the free end of which the upper end of a link 357 is pivotally connected.

It will be observed in Figures 1 and 12 that the lower end of link 357 is pivotally connected to one end of a lever 360 which end is normally urged upwardly by a tension spring 361. The lever 360 is oscillatably mounted intermediate its ends on a stub shaft 362 projecting outwardly from the left-hand side frame member 111. The front end of the lever 360 has a follower 363 thereon (Figures 3 and 12) which engages the periphery of an irregularly-shaped cam wheel 364 fixed on the cam shaft 140.

It is thus seen, that upon each successive carton or carrier blank B being positioned upon the die plate 11, the low surface of cam 364 (Figures 3 and 12) moves into engagement with follower 363 so the spring 361 (Figure 1) then imparts downward movement to the first fold punch 45, through intervening connections, to form a carton from the corresponding blank as it is forced through die 36 into the corresponding cup or pocket 51, 52 on the endless conveyor 47 in the manner heretofore described. Thereafter, the high surface of cam 364 engages the follower 363 to return the punch plate 45 to elevated position preparatory to a succeeding blank being positioned therebeneath with the next cycle in the operation of the machine in the manner heretofore described. It will be noted that the die plate 11 is suitably supported on the transverse frame members 115, 116 and its rear edge is preferably bent downwardly at an angle as shown in Figure 9 to insure that the leading edge of each successive blank will readily slide onto the plate 11.

Gluing mechanism

It has already been described how step-by-step movement is imparted to the conveyor 47, in the course of which the top wall 21 of each successive blank, previously formed into an open-topped carton, engages the downwardly and outwardly inclined top wall folding rod or deflecting rod 53 to maintain the carton thus formed in open position while an operator places articles, such as men's hose, in the carton. It should be noted that the top wall deflecting rod 53 is disposed adjacent the

lateral plane of the foot treadle plate 155 so the operator may stand or sit adjacent the foot treadle plate and thus control the advancement of each successive article in the manner heretofore described at the filling station defined by the rod 53.

It has also been described how the leading and trailing end flaps 24, 25 (Figure 16) of each successive carrier or carton B and the small or narrow overlap 20 are folded inwardly so they overlie the bottom or body portion 15 of the corresponding carton preparatory to the application of the adhesive 21a to the inner surface of the top wall 21 by the adhesive applying roller or wheel 56. The means for applying liquid adhesive or glue to the periphery of the adhesive applying roller or wheel 56 and the means for driving the same, as well as the means for driving the trailing flap knock-over cam 63 will now be described in detail.

The glue or adhesive applying mechanism 55 is best shown in Figures 1, 2, 6, 7-A, 8, 10-A, 11, 18 and 20.

It will be noted that the rear portions of the side frame members 111, 111' adjacent the stack supporting and elevating mechanism 230, the blank raising and feeding mechanism 10 and the first folding or carton forming mechanism 12 are relatively high as compared to the medial and front portions of these side frame members 111, 111'. Thus, a pair of substantially inverted L-shaped auxiliary side frame members 370, 370' are suitably secured at their lower ends to the respective side frame members 111, 111'. The auxiliary side frame member 370 is fixed to the outer surface of the main side frame member 111 and the auxiliary side frame member 370' is fixed to the inner surface of the main side frame member 111' (Figure 2).

As best shown in Figures 2, 10-A, 11 and 20, the glue applying roll or wheel 56 is fixed on the medial portion of a transverse shaft 371 and normally bears against an intermediate adhesive or glue-transfer roll or wheel 372 fixed on a transverse shaft 373. The transfer roll 372, in turn, is normally engaged by a glue or adhesive pick-up roll 374 fixed on the medial portion of a shaft 375. The shaft 373 is journaled in the horizontal upper portions of the auxiliary side frame members 370, 370' and one end thereof has a suitable hand wheel 376 fixed thereon and the other end thereof has a sprocket wheel 377 loose thereon (Figures 7-A and 1, respectively).

The sprocket wheel 377 is engaged by an endless sprocket chain 380 (Figures 1, 2, 6, 10-A and 20) which extends downwardly and engages a sprocket wheel 381 fixed on a relatively short shaft 382. It will be noted that the left-hand side frame member 111 is cut away to form an opening 383 (Figures 1 and 10-A) in the medial portion thereof adjacent the carton ejection guideway or chute 76. Therefore, the lower front portion of the auxiliary side frame member 370 projects forwardly and the shaft 382 is suitably journaled therein.

Shaft 382 also has a relatively small sprocket wheel 385 fixed thereon which is engaged by an endless sprocket chain 386 (Figures 1, 2, 2-A, 4 and 6) which, as best shown in Figure 1, also engages the sprocket wheel 141 which is continuously driven in the manner heretofore described.

Suitable belt or sprocket chain tensioning devices 387, 388 are adjustably secured to the auxiliary side frame member 370 for maintaining tension in the endless sprocket chains 380, 386. One end of shaft 371 loosely penetrates a suitable slot in the auxiliary side

frame member 370 and has a gear 390 fixed thereon (Figures 1, 2, 6 and 20) which engages a gear 391 fixed on the intermediate shaft 373 which gear also engages a gear 392 fixed on the rear shaft 375. The gears 390, 391, 392 are of relative sizes corresponding to the sizes of the rolls or wheels 56, 372, 374 so that all three of these rolls or wheels rotate at the same surface speed.

It will be observed in Figure 2 that the sprocket wheel 377, which is loose on shaft 373, transmits rotation to shaft 373 through the medium of a detent 393 slidably mounted in the hub of gear 391 and which is urged out-

wardly by a compression spring 394. The inner surface of the hub of sprocket wheel 377 has a beveled notch 395 therein whose flat wall engages the pin or detent 393 when the sprocket wheel 377 is driven. However, when the machine is not operating and the flow of current to the electric motor 126 is broken, the shaft 377 may be manually rotated in a clockwise direction in Figure 7-A by manipulation of the hand-wheel 376 so the three shafts 371, 373, 375 and their respective rolls or wheels 56, 372, 374 may be manually rotated without being encumbered by the electric motor 126 and the intervening parts between the electric motor 126 and the sprocket wheels 377, for cleaning the surfaces of the rolls 56, 372, 374, for example.

It will be observed in Figures 2, 6 and 20 that the end of shafts 371, 375 adjacent the gears 390, 392 and the auxiliary side frame member 370 are journaled in the lower ends of respective swing arms 396, 397 pivotally mounted on respective stub shafts 400, 401, fixed to and projecting outwardly from the left-hand auxiliary side frame member 370. The other ends of the shafts 371, 375 terminate in closely spaced relation to the right-hand auxiliary side frame member 370' and are journaled in the lower ends of respective swing arms 396', 397' whose upper ends are also journaled on respective stub shafts 400', 401' projecting inwardly from the auxiliary side frame member 370' (Figures 2, 7-A, 8 and 20).

It will be noted that the lower ends of the swing arms 397, 397' depend below the horizontal upper portions of the inverted L-shaped auxiliary frame members 370, 370' so the shaft 375 extends beneath the frame member 370. The shafts 371, 375 are mounted in the manner described in order to accurately predetermine the amount and density of the liquid adhesive or glue which is transferred to the glue applying roll 56 from a reservoir or supply tank 402 in which the lower portion of the pick-up roll or wheel 374 is partially immersed during normal operation of the machine. It is apparent that the pick-up roll 374 transfers the liquid adhesive from the reservoir 402 to the periphery of the transfer roll 372 which, in turn, transfers a uniform film of liquid adhesive or glue to the periphery of the glue applying roll 56.

The swing arms 396, 397' have the distal ends of respective tension springs 405, 406 connected thereto (Figure 8). The proximal ends of springs 405, 406 are connected to the auxiliary side frame member 370'. Inward movement of the swing arms is limited by adjustment screws 407, 408 which threadably penetrate the respective swing arms 396, 397' and whose proximal or inner ends are urged against respective stops or abutments 411, 412 carried by the auxiliary frame member 370'. Springs, screws and stops similar to the respective elements 405, 406, 407, 408, 411 and 412 may be provided for swing arms 396, 397, if desired.

In order to prevent excessive accumulation of adhesive material or glue on the periphery of the pick-up roll 374, a suitable dressing blade or scraper blade 413 (Figures 10-A and 11) is disposed closely adjacent the periphery of the pick-up roll 374 and is fixed on the lower end of an arm or bracket 415 which extends upwardly between the shafts 371, 373 and is adjustably secured on a transverse rod or shaft 416 whose opposite ends are fixed in the uppermost portions of the auxiliary side frame members 370, 370'.

The reservoir 402 is shown in the form of a substantially rectangular open-topped container which rests upon a vertically movable platform 420 whose opposite ends preferably have upwardly curved deflector fingers 421 thereon. The fingers 421 are provided to insure that the outwardly deflected top wall 21 of each successive carton B passes therebeneath as it is advanced thereby on the conveyor 47. The reservoir platform 420 overlies the upper edge of side frame member 111 and is fixed to the upper end of a guide post 423 mounted for vertical

sliding movement in a guide block 424 suitably secured to the outer surface of side frame member 111.

5 A bearing block 425, fixed to the upper surface of side frame member 111, has a shaft 426 journaled therein, to the inner end of which an eccentric cam wheel 427, having a flattened surface 427a thereon, is suitably secured (Figures 10-A and 11). The eccentric cam 427 has a handle 430 projecting inwardly therefrom (Figure 20) which is adapted to be grasped by the operator for 10 manually rotating the cam 427 for raising and lowering the platform 420 and the reservoir 402 thereon for obvious reasons. It is thus seen that a uniform film of liquid adhesive is applied to the top wall 21 of each successive carton B by the adhesive applying roll 56.

The trailing end-flap knock-over cam 63 is fixed on the inner end of a relatively short shaft 435 rotatably mounted in the right-hand auxiliary side frame member 370' at the juncture of the horizontal and vertical legs thereof (Figure 7-A). The outer end of shaft 435 has a gear 436 fixed thereon which meshes with a gear 437 fixed on a stub shaft 440 (Figures 7-A and 20) also journaled in the auxiliary side frame member 370'. The shaft 440 also has a sprocket wheel 441 fixed thereon which is engaged by the endless sprocket chain 442. The sprocket chain 442 is also mounted on a sprocket wheel 443 (Figures 2 and 20) fixed on the front cam shaft 163.

25 Since the cam shafts 140, 163 rotate a complete revolution with each step in movement by the conveyor 47, it is apparent that the knock-over cam 63 is also rotated a single revolution with each step in movement of the conveyor 47 so that the flat surface 64 on the cam 63 (Figures 8 and 18) engages and folds the trailing end-flap 25 on each successive carton or carrier downwardly 30 so it will readily pass beneath the top plate 60 of the second folding mechanism 55 in the manner heretofore described.

Carton ejector mechanism

35 As heretofore stated, after the adhesive has been applied to the outturned top wall 21 of each successive carton or blank B at the second folding mechanism 55, it is then folded inwardly over the front portion of plate 60 (Figure 18) by the top wall folding element 71 as the corresponding carton is positioned adjacent the inner end of the carton ejection guideway 76, whereupon 40 the lateral portion of the ejector plunger 75 then moves from right to left in Figure 13 to move the corresponding carton off of the conveyor 47 and into the discharge or carton ejection chute 76. The ejector mechanism 50 will now be described in detail.

45 The ejector plunger 75 extends outwardly and has an upwardly projecting off-set portion 450 (Figure 6) on its outer end which is fixed to a transversely reciprocable ejector guide bar 451 mounted for horizontal sliding movement in a guide bracket 452. It will be observed 55 in Figures 1, 2, 6, 7-A and 13 that the guide block 452 has a web portion 453 extending forwardly and downwardly therefrom which is suitably secured to the outer surface of the conveyor side track 221'.

60 Referring to Figures 2, 6, 7-A and 13, it will be observed that the outer end of the ejector guide bar 451 has one end of a composite link 455 pivotally connected thereto which is provided with a reduced outer portion 456 which loosely penetrates a sleeve 457 and a pivot pin 460 in the upper end of a crank 461. A compression spring 462 encircles the reduced portion 456 of link 455 and is disposed between the enlarged portion of said link and the sleeve 457 to thus normally urge the sleeve 457 against an abutment or lock nut 463 on the outer end of the reduced portion 456 of the composite link 455.

65 The composite link 455 has a resilient bumper 464 adjustably mounted thereon which, in the course of inward movement of the upper end of crank 461, passes through 70 a slot 465 (Figure 6) formed in the guide block 452 and

engages the web portion 453 so that each successive filled carton is accurately positioned above the printing mechanism, 87, since the spring 462 (Figure 13) will then permit the upper end of crank 461 to move inwardly relative to the link 455. The lower end of crank 461 is fixed on a horizontally disposed shaft 470 journaled in a bearing bracket 471 suitably secured to and projecting outwardly from the right-hand side frame member 111' (Figures 2, 7-A and 13).

The rear end of shaft 470 (Figure 7-A) has a crank 472 fixed thereon and projects outwardly therefrom (Figure 20) which is pivotally connected to a vertically reciprocable yoke member 473 by means of an overriding mechanism comprising an extension 474 pivotally connected to the upper end of the yoke member 473, as at 475 (Figures 6 to 20). It will be noted that the outer end of crank 472 has a pivot pin or stub shaft 476 thereon (Figures 7-A and 20) which normally seats against the inner surface of the extension 474 and also seats in an arcuate cavity provided therefor in a pivoted arm 477. Arm 477 is pivotally connected, as at 480, to the lower portion of the yoke extension 474.

The upper end of arm 477 has one end of a screw 481 threadably embedded therein which loosely penetrates the upper portion of the yoke extension 474 and is surrounded by a compression spring 482 which, thus, normally urges the upper end of arm 477 against the inner surface of the yoke extension 474. The upper end of arm 477 also has a normally open switch 483 fixed thereon which is also interposed in the electrical circuit to the electric motor 126 (Figure 1) and which is normally held in closed position by engagement with the upper end of the yoke extension 474. Thus, upon any obstruction preventing inward movement of the ejector plunger 75, the extension 474 and arm 475 will move upwardly relative to the pivot pin 476 and the crank 472 which will thereby move the arm 477 inwardly relative to yoke extension 474, permitting the switch 483 to open, to thereby break the circuit to the electric motor 126 and to stop the machine.

It will be best observed in Figure 7-A that the lower end of the yoke 473 straddles the front cam shaft 163, is guided thereon and has a follower 485 thereon which engages an irregular groove 486 in the face cam 487 fixed on the cam shaft 163. It is apparent, from the shape of the groove 486 in face cam 487 in Figure 7-A, that the cam 487 imparts inward and outward movement to the plunger 75 and its lateral portion 74 in the interim between each advancement of the conveyor 47 to thereby move the corresponding filled carton formed from a blank B into the discharge chute or guideway 76 and beneath the carton top wall seating or hold-down plate 73, in the manner heretofore described, to thereby position the corresponding filled carton above the then lowered printing plate or plates 87 (Figures 13, 14 and 15).

Printing mechanism

It has already been described how the printing plate 87 of the printing mechanism 85 moves upwardly and impinges against the lower surface of each successive filled carton as it is projected off the conveyor 47. The means for controlling the printing mechanism will now be described in detail. Referring to Figures 1, 13 and 14, it will be observed that the upper portion of the printing plunger or arm 90 has a projection or block 490 thereon for supporting the printing block 86, said printing block 86 being resiliently secured on the projection or block 490 by a plurality of spring clips 491.

The upper portion of the printing plunger 90 is mounted for vertical sliding movement in a dove-tailed guide 492 (Figures 1, 6, 8, 10-A, 14 and 15). The laterally projecting upper portion of the guide 492 is suitably secured to the lower surface of the bottom 220 of the track assembly 217. The upper end of a link 493 is pivotally connected to the lower portion of plunger 90

and the lower end of link 493 is connected to the front end of one arm of a bell crank 495 pivotally mounted on a stub shaft 496 carried by the side frame member 111 (Figures 10-A and 13).

The bell crank 495 is normally urged in a counterclockwise direction in Figure 10-A by a tension spring 497 whose lower end is connected to the substantially horizontal arm of bell crank 495 and whose upper end is connected to a suitable spring anchor 500 carried by the track assembly 217 (Figures 10-A and 20). The relatively short substantially vertical leg of bell crank 495 has the front end of a link 501 pivotally connected thereto whose rear end has a yoke member 503 (Figure 10) thereon whose bifurcated rear end is guided upon and slides in engagement with the hub of an irregularly-shaped cam wheel 505 fixed on the rear transverse cam shaft 140. The yoke 503 (Figures 10 and 12) has a follower 506 thereon which is urged against the periphery of cam wheel 505 by the tension spring 497 in Figure 10-A.

It is thus seen that, each time a step in movement is imparted to the conveyor 47, the low surface of cam 505 moves into engagement with follower 506 thereby permitting spring 497 to move plunger 90 and its printing block 86 (Figures 13 and 14) upwardly for printing the desired indicia on the lower surface of the bottom wall 15 of the carton formed from the corresponding blank B. In order to accurately determine the level to which the printing plate 87 is elevated, the plunger 90 has an adjustable resilient abutment or stop 507 (Figures 10-A and 13) thereon which engages the lower surface of the guide 492.

Inking mechanism

As heretofore stated, in the course of upward movement of the printing plate 87 in Figure 13, it engages the resilient ink pad 91 which then moves out of the vertical path of upward movement of the printing plate 87. Now, referring to Figure 13, it will be observed that the ink pad 91, which may be impregnated with a suitable ink material, is adhesively or otherwise secured to the lower surface of a block 510 on the free inner end of a pivoted arm 511 which is pivotally mounted, as at 512, on an inking guide member 513 mounted for transverse sliding movement on a dove-tailed guide bar 514.

It will be observed in Figures 1 and 10-A that the ink applying mechanism is disposed within the opening 383 in the front portion of the side frame member 111 and, therefore, the guide bar 514 is suitably secured to a bracket 515 which extends forwardly and is secured to the side frame member 111. Referring again to Figure 13, it will be observed that the inner portion of the arm 511 has an adjustable stop or set screw 516 therein which is normally urged against a projection 517 on the rear surface of the guide block 513 by a tension spring 520. The outer end of tension spring 520 is fixed to an upwardly projecting arm 521 integral with arm 511 and the inner end of spring 520 is suitably connected to the inking carriage 513.

The upper portion of the inking carriage 513 in Figure 13 has the corresponding end of a link 522 pivotally connected thereto (Figures 2, 6, 8 and 13) which loosely extends through suitable openings provided therefor in the side tracks 221, 221' and whose other end is pivotally connected to the lower end of a crank 524. The upper end of crank 524 is fixed on the front end of a shaft 525 journaled in a standard 526 which extends downwardly and is integral with the bearing bracket or block 471 heretofore described.

The rear end of shaft 525 has a crank 527 fixed thereon (Figures 2, 7-A and 8). The upper end of a link 530 is pivotally connected to the free end of crank 527 and the lower end of link 530 has a yoke member 531 fixed thereto whose bifurcated lower end straddles and is guided on the front transverse cam shaft 163 as best shown in Figure 8. The yoke 531 has a follower 533 thereon

which engages groove 534 in one face of cam wheel 206.

It is apparent from the foregoing description that the groove 534 in the cam wheel 206 causes lateral reciprocation of the inking carriage 513 and the shape of cam wheel 505 (Figure 10) relative to the groove 534 in cam wheel 206 (Figure 8) is such that the inking carriage 513 moves inwardly while the plunger 90 is in lowered position so the ink pad 91 is disposed above the printing plate 87 (Figure 13) at the time that upward movement of the plunger 90, printing block 86 and printing plate 87 is initiated. In the course of upward movement of the printing plate 87, it engages and raises the ink pad 91 whereupon the high portion of the groove 534 in cam wheel 206 engages the follower 533 to impart outward movement to the inking carriage 513. In so doing, the ink pad slides off the upper end of the then upwardly moving printing plate 87 whereupon the screw 516 then comes to rest against the projection 517 on the inking carriage 513 during the completion of the printing operation.

Carton cover pressure applying mechanism

As heretofore stated, the filled or completed carriers or cartons are moved along the discharge chute or guideway 76 in juxtaposition as each successive filled carton is moved off of the conveyor by the lateral portion 74 of the ejector plunger 75. After the indicia has been applied or printed on the bottom of each successive carton, as the next succeeding carton is projected into position above the printing mechanism 85, any preceding cartons are moved beneath the resilient pressure applying elements or ribs 96 carried by the pressure applying plates 97. The means for operating the pressure applying plate 97 will now be described in detail.

Referring to Figures 1, 2, 6, 10-A, 13 and 18, it will be observed that the pressure applying plate 97 is suitably secured to or integral with the rear end portion of a plate or bar 540 whose front portion is fixed on the upper end of a vertically disposed slide bar 541 mounted for vertical sliding movement in a suitable guide bracket 542 which is, in turn, suitably secured to the inner surface of the bracket 515 heretofore described. The lower end of the slide bar 541 has a follower extension bar 544 (Figure 10-A) suitably secured thereto whose lower end has a follower 545 thereon which is adapted to, at times, be engaged by a cam plate 546 integral with or suitably secured to a crank arm 547 which extends forwardly and is fixed on the rocker shaft 200.

It will be observed in Figures 6 and 10-A that the rocker shaft 200 also has the upper end of a crank 550 fixed thereto, to the lower end of which the front end of a link 551 is pivotally connected. The rear end of link 551 has a yoke member 552 (Figures 10-A and 20) fixed thereto which straddles and is guided upon the cam shaft 163. The yoke member 552 has a cam follower 553 thereon which engages the periphery of an irregularly-shaped cam wheel 554 fixed on the cam shaft 163. The cam follower 553 is urged into engagement with the periphery of cam wheel 554 by means of a tension spring 555, the rear end of which is suitably connected to the base 110 and the front end of which is connected to the crank 550.

The cam wheel 554 is so formed that, as each successive filled carrier or carton is moved off the conveyor 47 by the lateral portion 74 on the ejector plunger 75, the low surface of cam 554 is in engagement with the follower 553 and, consequently, the lower surfaces of the resilient pressure applying elements 96 are spaced above the level of the lower surface of the top flap hold-down plate 73. However, as the next succeeding step is imparted to the conveyor 47, the high surface of cam 554 engages follower 553 to move the cam plate 546 downwardly, whereupon the resilient pressure applying elements 96 rest upon the top wall 21 of the corresponding carton or carrier to thereby press the

same against the narrow overlap portion 20 of the corresponding carton (Figure 16) while the liquid adhesive is setting or becoming solidified to thereby tightly seal the top wall portion 21 in engagement with the overlap 20 of the corresponding carton B.

It is apparent that, in the absence of a carton beneath the pressure applying plate 97, the follower 545 will remain in engagement with the upper surface of the cam plate 546 during downward movement thereof, as effected by the means heretofore described, throughout a substantial part of downward movement of the cam plate 546. However, downward movement of the pressure applying plate 97 and its associated parts is limited by a resilient bumper 557 (Figure 6) adjustably secured to the upper surface of the guide bracket 542 heretofore described.

The slide bar 541 has an abutment 560 thereon, which is shown in the form of an angle clip, which rests against the upper end of the adjustable bumper 554 when the high surface of cam 554 (Figure 10-A) is in engagement with the cam follower 553. It will be observed in Figures 1, 2 and 6 that the carton ejector chute or discharge chute 76 is supported on a suitable built-up substantially Z-shaped bracket 565 which extends inwardly in Figure 6 and is suitably secured to the bracket 515.

It is thus seen that we have provided a novel carton or carrier forming and sealing machine having efficient and novel means for successively picking up carton blanks, one at a time, from a novel form of stack elevating apparatus and transferring the corresponding blank onto a novel form of first folding mechanism which forms each successive carton blank into an open-topped container with a single active stroke of the punch 45 so that articles may subsequently be positioned in the container then disposed on the conveyor 47 and wherein a novel form of gluing mechanism is provided for applying glue or other adhesive material to the top wall of the container, after which the top wall is folded over the end flaps and the opposite side overlap of the container.

Also, it is seen that we have provided a novel form of means for bending the trailing end flap so that it will pass beneath the end flap folding die plate 60 and whereby each successive filled carton or carrier is then ejected from the conveyor into an uniquely constructed discharge chute having novel automatic means for printing desired indicia on the lower surface of each successive carton and also having novel means for, thereafter, applying pressure to each successive carton to insure that the top wall of each carton is tightly held against the overlap on the opposite side wall of the carton while the liquid adhesive is drying to thereby tightly seal the carton or carrier or, at least, to thereby tightly secure the free edge of the topwall of each successive carton to the overlap extending from the opposite side wall of the carton or carrier.

There are various ways in which the electrical circuit for motor 126 and other electrical components of the present machine may be arranged. Therefore, a description thereof is deemed unnecessary.

In the drawings and specifications there has been set forth a preferred embodiment of the invention and although specific terms are employed, they are used in a generic and descriptive sense only and not for purposes of limitation, the scope of the invention being defined in the claims.

We claim:

1. In a machine for forming a container from a flat substantially cross-shaped blank having a rectangular base portion, first and second side panels connected to opposite side edges of the base portion, first and second end panels connected to opposite end edges of the base portion and a tab connected to each end of each side

panel and adjacent the corresponding end panel; in combination, means for successively conveying containers in blank form into the machine one at a time, means for folding the tabs inwardly in substantially perpendicular relation to the corresponding side panels, means for then folding the four spaced panels upwardly in perpendicular relation to said base portion whereby the lower portions of the end panels lie against the corresponding tabs, means for folding the upper portion of the first end panel and a corresponding portion of the second end panel inwardly toward each other to overlie said base portion, means for folding the upper portion of the first side panel across the upper surfaces of said portions of the first and second end panels, means to render a portion of at least the second side panel adhesive, and means for folding the upper portion of the second side panel across said portions of the first and second end panels and against the first side panel for adhesively securing the said last named portion of the second side panel to the then upper surface of said portion of the first side panel.

2. A structure according to claim 1 having means operable automatically upon said portion of the second side panel being adhesively secured to said portion of the first side panel for printing indicia on the container thus formed.

3. A machine for forming a closed container from a flat substantially cross-shaped blank having a substantially rectangular base portion and four panels projecting from the respective four edges of said main base portion, said machine comprising a substantially vertically disposed substantially rectangular tubular die, a magazine for supporting a stack of blanks rearwardly of said die, means for successively feeding the containers in blank form from the magazine onto the tubular die one at a time, the internal dimensions of said tubular die being substantially the same as the dimensions of said base portion of the container, a series of substantially rectangular pockets, means for successively positioning pockets beneath and in vertical alinement with said die in timed relation to the feeding means, means for forcing each successive blank downwardly through said tubular die to thereby fold the panels upwardly at the four edges of said base portion, the depth of said pockets being substantially less than the height of each panel thus extended upwardly, means for folding one of the side panels of each successive container outwardly as it is advanced, means for rendering adhesive at least a portion of said outwardly folded portion of said one of the side panels, means for successively folding the upper portions of the two end panels inwardly to overlie said base portion, and means for then successively folding the upper portion of the other of said side panels and the upper portion of said one of the side panels inwardly to overlie said base portion.

4. A structure according to claim 3 wherein said magazine and said feeding means comprise a platform for supporting a stack of blanks, a grasping device disposed above the stack, means operable automatically in timed relation to said pocket positioning means for actuating the grasping device to move the same downwardly against the stack, upwardly and forwardly to a position above said die and to then return the grasping device to its original position, said grasping device having means thereon for grasping the uppermost blank in the stack as it moves downwardly to thereby position said uppermost blank above the die and below the forcing means, means to release each successive blank from the grasping means as it is positioned above said die, and means operable automatically to raise the platform upon the then uppermost blank thereon being spaced a predetermined distance below the grasping device to properly position the latter blank for subsequent engagement by the grasping device.

5. A machine for forming a closed container from a flat substantially cross-shaped blank having a substantially

rectangular base portion and four panels projecting from the four edges of said base portion, said machine comprising a substantially vertically disposed substantially rectangular tubular die, means supporting a stack of blanks rearwardly of said die, means for successively conveying the containers in blank form on to the tubular die one at a time, the internal dimensions of said tubular die being substantially the same as the dimensions of said base portion of the container, a series of substantially rectangular pockets, means for successively positioning pockets beneath and in vertical alinement with said die, means for forcing each successive blank downwardly through said tubular die and into a pocket therebeneath to thereby fold the panels upwardly at the four edges of said base portion to form two opposed end panels and two opposed side panels, the depth of said pockets being substantially less than the height of each panel thus extended upwardly, means for folding the upper portion of one of the side panels of each successive container outwardly as it is advanced, means for rendering adhesive at least a portion of said outwardly folded portion of said one of the side panels, means for successively folding the upper portions of the two end panels inwardly to overlie said base portion, means for then successively folding the upper portion of the other of said side panels and the upper portion of said one of the side panels inwardly in overlapping relationship, means for then discharging each successive container laterally from said series of pockets, means automatically operable for then applying pressure to the container to cause the adhesive portion of said one of the side panels to adhere to said portion of the other of said side panels, and means automatically operable for printing indicia on each successively discharged container.

6. In a structure according to claim 5, said pockets each comprising a pair of longitudinally spaced laterally extending angle plates, an intermittently movable conveyor supporting said angle plates and a pair of longitudinally extending stationary side wall guiding bars between which the angle plates are advanced, said discharge means comprising a discharge chute extending outwardly from a point closely adjacent said conveyor and at a point beyond the front end of one of the side wall guiding bars, an ejector plunger normally disposed on the side of the conveyor opposite from said discharge chute, means operable automatically upon each successive pocket being alined with said chute for imparting inward and then outward movement to the ejector plunger to cause the same to move between the angle plates of the corresponding pocket to thereby move the corresponding container into said chute.

7. In a structure according to claim 6, said means for applying pressure to the container comprising a pressure applying element spaced above the bottom of said discharge chute, means automatically operable with actuation of said ejector plunger for raising said pressure applying element above the level of the upper surface of the corresponding container as it is ejected into said discharge chute, and means operable automatically during subsequent advancement of said conveyor for releasing said pressure applying element to permit the same to bear against the upper surface of the corresponding container.

8. In a structure according to claim 5, said printing means comprising a printing block normally spaced below the chute, the bottom of said chute having an opening therein alined with said printing block, means automatically operable for imparting upward movement to the printing block upon each successive container being ejected into said chute, means automatically operable in the course of such upward movement for applying ink to the printing block whereby, with further upward movement of the printing block, the printing block marks indicia on the lower surface of the corresponding container.

9. That method of forming a closed container from a flat blank having a rectangular base portion and first

and second opposed side panels and first and second opposed end panels projecting outwardly from the four edges of said base portion and a relatively small tab projecting outwardly from each side edge of each side panel which comprises successively forcing the blank through a cross-shaped opening formed in a plate and through a rectangular tubular die to cause the tabs to project inwardly from the side panels and to then cause the side panels and end panels to project upwardly from said base portion, positioning the container thus formed in a rectangular pocket for maintaining the upright attitude of said side and end panels relative to said base portion, placing articles to be packaged in the container, applying liquid adhesive to the upper portion of the first side panel, successively folding the upper portions of the first and second end panels inwardly across the upper edges of the tabs to overlie said base portion, and then successively folding the upper portions of the second and first side panels over the inwardly folded portions of the first and second end panels whereby the upper folded portion of the first side panel will adhere to the upper folded portion of the second side panel.

10. That method of forming a closed container from a flat blank having a rectangular base portion and first and second opposed side panels and first and second opposed end panels projecting outwardly from the four edges of said base portion which comprises forcing the blank through a rectangular tubular die to cause the side panels and end panels to project upwardly from said base portion, positioning the container thus formed in a rectangular pocket for maintaining the upright position of said side and end panels relative to said base portion, then rendering adhesive the upper portion of the first side panel, successively folding the upper portions of the first and second end panels inwardly to overlie said base portion, and then successively folding the upper portions of the second and first side panels over the inwardly folded portions of the first and second end panels whereby the upper folded portion of the first side panel will adhere to the folded portion of the corresponding panel therebeneath.

11. In a machine for forming a container from a flat substantially cross-shaped blank having a central base portion and four circularly spaced substantially rectangular panels thereon, said machine having an intermittently movable conveyor in combination, means for successively conveying containers in blank form into the machine, one at a time, means for folding the four shaped panels upwardly in perpendicular relation to said base portion to form first and second spaced side panels and first and second spaced end panels on the container, a series of open-topped substantially rectangular pockets on said conveyor, said pockets being movable, one at a time, into position below said folding means for receiving the lower portion of each successive container thus folded, means for folding the upper portion of the first end panel and a corresponding portion of the second end panel inwardly toward each other to overlie said base portion with movement of each successive container from below said first-named folding means, means for folding a portion of the first side panel across the upper surfaces of said portions of the first and second end panels, means to render a portion of the second side panel adhesive, means for folding a portion of the second side panel across said portions of the first and second end panels and the first side panel for adhesively securing the said last-named portion of the second side panel to the then upper surface of said portion of the first side panel, said pockets each comprising a pair of longitudinally spaced laterally extending angle plates supported on said intermittently movable conveyor and a pair of longitudinally extending stationary side wall guiding bars between which the angle plates are advanced, means for discharging each successive container from its corresponding pocket comprising a discharge trough

extending outwardly from a point closely adjacent said conveyor and at a point beyond the front end of the corresponding side wall guiding bar, an ejector plunger normally disposed on the side of the conveyor opposite from said discharge trough, means operable automatically upon each successive pocket being aligned with said trough for imparting inward and then outward movement to the ejector plunger to cause the same to move between the angle plates of the corresponding pocket to thereby move the corresponding container into said trough, printing means comprising a printing block normally spaced below the trough, said trough having an opening therein aligned with said printing block, means automatically operable for imparting upward movement to the printing block upon each successive container being ejected into said trough, and means automatically operable in the course of such upward movement for applying ink to the printing block whereby, with further upward movement of the printing block, the printing block marks indicia on the lower surface of the corresponding container.

12. A structure according to claim 11 having means for applying pressure to each successive container for setting said adhesive comprising a pressure applying element spaced above the bottom of said discharge trough, means automatically operable with actuation of said ejector plunger for raising said pressure applying element above the level of the upper surface of the corresponding container as it is ejected into said discharge trough, and means operable automatically following the ejection of each successive container into the trough for releasing said pressure applying element to permit the same to bear against the upper surface of the corresponding container.

13. In a machine for forming substantially rectangular containers from cross-shaped blanks of the type having a rectangular bottom, first and second opposed side walls, first and second opposed end walls, a first short side overlap on the outer end of the first side wall, a second relatively long side overlap on the outer end of the second side wall and first and second end overlaps on the outer ends of the respective first and second end walls, said machine having a conveyor and means for feeding blanks, one at a time, into the machine; the combination of a substantially rectangular tubular die, of substantially the same size as the bottom of said blank, spaced above said conveyor, the upper ends of the walls of said die having upwardly diverging portions thereon, a die plate formed integral with the outer ends of said upwardly diverging portions and onto which each successive blank is fed, said conveyor having a plurality of spaced substantially rectangular pockets thereon successively movable into registration with the lower end of said die, a vertically reciprocable punch plate normally spaced above the level of said die plate, means automatically operable upon each successive pocket registering with said die for imparting a downward and then an upward stroke to said punch plate whereby the side walls and side overlaps and end walls and end overlaps of said blank are folded upwardly relative to the bottom as the blank is forced through said die and into the corresponding pocket to form a rectangular container therefrom, means for successively folding the first and second end overlaps inwardly to overlie said bottom with subsequent movement of said conveyor, means for folding the first side overlap inwardly to overlie said bottom, means for applying adhesive material to at least a portion of said second side overlap, means for then folding the second side overlap over the first and second end overlaps and the first side overlap to adhesively secure the second side overlap to the first side overlap, said means for applying adhesive to the second side overlap of each successive container including a relatively narrow applicator wheel mounted on a horizontal axis and disposed above and to one side of the path of travel of said pockets, means for folding the second side overlap outwardly relative to said pockets in advance of move-

ment of the corresponding container past said applicator wheel, and means for driving said applicator wheel at a peripheral speed corresponding to the rate of movement of each successive container thereby.

14. In a machine for forming substantially rectangular containers from cross-shaped blanks of the type having a rectangular bottom, first and second opposed side walls, first and second opposed end walls, a first short side overlap on the outer end of the first side wall, a second relatively long side overlap on the outer end of the second side wall and first and second end overflaps on the outer ends of the respective first and second end walls, said machine having a conveyor and means for feeding blanks, one at a time, into the machine; the combination of a substantially rectangular tubular die, of substantially the same size as the bottom of said blank, spaced above said conveyor, the upper ends of the walls of said die having upwardly diverging portions thereon, a die plate formed integral with the outer ends of said upwardly diverging portions and onto which each successive blank is fed, said conveyor having a plurality of spaced substantially rectangular pockets thereon successively movable into registration with the lower end of said die, a vertically reciprocable punch plate normally spaced above the level of said die plate, means automatically operable upon each successive pocket registering with said die for imparting a downward and then an upward stroke to said punch plate whereby the side walls and side overflaps and end walls and end overflaps of said blank are folded upwardly relative to the bottom as the blank is forced through said die and into the corresponding pocket to form a rectangular container therefrom, means for successively folding the first and second end overflaps inwardly to overlie said bottom with subsequent movement of said conveyor, means for folding the first side overlap inwardly to overlie said bottom, means for applying adhesive material to at least a portion of said second side overlap, means for then folding the second side overlap over the first and second end overflaps and the first side overlap to adhesively secure the second side overlap to the first side overlap, said means for successively folding the first and second end overflaps comprising a substantially horizontal folding plate spaced above the path of travel of said conveyor a distance somewhat greater than the height of the first and second end walls and the first and second side walls of the container, said folding plate having an upwardly curving rear edge engageable by the first end overlap for folding the latter into substantially horizontal position as the corresponding container moves therebeneath, a normally stationary knock-over cam disposed immediately adjacent the rear upwardly curved edge of said folding plate and having a radial surface thereon adapted to move into engagement with the outer surface of each successive second end overlap and to then move the same inwardly and downwardly to substantially horizontal position to pass beneath the folding plate, and means operable automatically upon each successive container moving into position beneath said folding plate to impart movement to said knock-over cam.

15. A structure according to claim 14 wherein said means for folding the first side overlap inwardly includes a side folding plate spaced from one side edge to the horizontal folding plate and having an inwardly and downwardly spiraling portion spaced from the rear edge thereof and merging with said horizontal folding plate and in engagement with which the first side overlap moves with advancement of the corresponding container for folding the first side overlap beneath the immediately adjacent portion of said horizontal folding plate.

16. In a machine for forming substantially rectangular containers from cross-shaped blanks of the type having a rectangular bottom, first and second opposed side walls, first and second opposed end walls, a first short side overlap on the outer end of the first side wall, a

second relatively long side overlap on the outer end of the second side wall and first and second end overflaps on the outer ends of the respective first and second end walls, said machine having a conveyor and means for feeding blanks, one at a time, into the machine; the combination of a substantially rectangular tubular die, of substantially the same size as the bottom of said blank, spaced above said conveyor, the upper ends of the walls of said die having upwardly diverging portions thereon, a die plate formed integral with the outer ends of said upwardly diverging portions and onto which each successive blank is fed, said conveyor having a plurality of spaced substantially rectangular pockets thereon successively movable into registration with the lower end of said die, a vertically reciprocable punch plate normally spaced above the level of said die plate, means automatically operable upon each successive pocket registering with said die for imparting a downward and then an upward stroke to said punch plate whereby the side walls and side overflaps and end walls and end overflaps of said blank are folded upwardly relative to the bottom as the blank is forced through said die and into the corresponding pocket to form a rectangular container therefrom, means for successively folding the first and second end overflaps inwardly to overlie said bottom with subsequent movement of said conveyor, means for folding the first side overlap inwardly to overlie said bottom, means for applying adhesive material to at least a portion of said second side overlap, means for then folding the second side overlap over the first and second end overflaps and the first side overlap to adhesively secure the second side overlap to the first side overlap, each of said pockets including a longitudinally spaced pair of outwardly projecting lateral plates carried by said conveyor and a pair of substantially vertically disposed stationary side wall guiding plates between which the lateral plates pass with movement of said conveyor, said means for successively folding the first and second end overflaps comprising a substantially horizontal folding plate positioned upon one of the side wall guiding plates, overlying the other side wall guiding plate and having an upwardly curving rear edge engageable by the first end overlap for folding the latter into substantially horizontal position as the corresponding container moves therebeneath, a normally stationary knock-over cam disposed immediately adjacent the rear upwardly curved edge of said horizontal folding plate and having a radial surface thereon adapted to move into engagement with the outer surface of each successive second end overlap and to then move the same inwardly and downwardly to substantially horizontal position to pass beneath the folding plate, means operable automatically upon each successive container being moved into position beneath said folding plate to impart movement to said knock-over cam, said means for folding the first side overlap inwardly including a first side folding plate spaced from one side edge of the horizontal folding plate and having an inwardly and downwardly spiraling portion spaced from the rear edge thereof and merging with said horizontal folding plate and in engagement with which the first side overlap moves with advancement of the corresponding container for folding the first side overlap inwardly and beneath the immediately adjacent portion of said horizontal folding plate, said means for folding the second side overlap inwardly over the rest of the overflaps of the corresponding containers including a second relatively thin vertically disposed side overlap folding plate having its upper edge disposed on substantially the same level as said side wall guiding plates and also being spaced outwardly of the guiding plate remote from the first side folding plate, and said relatively thin plate having a relatively narrow spirally-formed front end portion extending inwardly and overlying the corresponding side wall guiding plate at a point forwardly of the spiraling portion of the first side folding

plate and forwardly of the horizontal folding plate to thereby cause the second end overlip of each successive container to move upwardly, inwardly and then downwardly as it rides in engagement with the spirally formed portion of said second side overlip folding plate.
